UNITED STATES PATENT OFFICE.

WILLIAM H. CARTER, OF NEEDHAM HEIGHTS, MASSACHUSETTS, ASSIGNOR, BY MESNE ASSIGNMENTS, TO THE WILLIAM CARTER CO., OF NEEDHAM HEIGHTS, MASSACHUSETTS, A CORPORATION OF MASSACHUSETTS.

BORDER FOR FABRICS.

1,072,380.

Specification of Letters Patent.

Patented Sept. 2, 1913.

Application filed March 29, 1911. Serial No. 617,627.

To all whom it may concern:

Be it known that I, WILLIAM H. CARTER, a citizen of the United States, and a resident of Needham Heights, in the county of Norfolk and State of Massachusetts, have invented an Improvement in Borders for Fabrics, of which the following description, in connection with the accompanying drawings, is a specification, like characters on the drawings representing like parts.

This invention relates to a fan crochet stitch fabric border.

In order that the invention may be clearly understood I shall disclose one form of my invention and the best mode now known to me for producing the same.

In the drawings: Figure 1 is a side elevation illustrating mechanism by which my fabric border may be produced; Fig. 2 is a similar view but showing the parts differently positioned; Fig. 3 is a plan view somewhat diagrammatic of a fan crocheted stitch border fabric embodying my invention; Fig. 4 is a diagrammatic view of a single set of stitches constituting the shell or cluster of my invention; Fig. 5 is a view similar to Fig. 3 of a double fabric border; Fig. 6 is a plan view of a stitching forming finger that may be employed in the practice of my invention; and Fig. 7 is a diagrammatic view indicating the relation of the thread manipulating elements that may be employed in practising my invention.

Ornamental borders for knitted or other fabrics, such as under-garments, are well known. The patents to Merrow, No. 413,077, October 15, 1889, and No. 414,233, November 5, 1889, clearly disclose the same. The said borders are therein represented as composed of a series of clusters or shells, each consisting of a series of radiating or generally fan-shaped stitches formed by an eye pointed machine needle, a crochet hook or knitting needle, and a hook for a supplemental thread. The clusters or shells are formed in *seriatim*, and the main and supplemental threads thereof are preferably continuous throughout the border. The stitches or loops forming the ribs of the clusters or shells shown in said Merrow patents are laid along substantially true radial lines and extend in fan shape both to the

right and to the left of a median line drawn from the center of the cluster to the edge of the fabric at right angles to said edge. 55

One of the objects of my invention is to produce a border composed of a connected series of shells or clusters wherein the stitches or loops all tend in the same general direction,—that is, toward the right 60 or toward the left as the observer looks toward the fabric; or wherein the threads or loops are so laid that the impression gained by the observer is that of a series of loops extending to the right or to the left as 65 stated.

In carrying out my invention I preferably also supply an increased amount of thread in the formation of the loops or stitches, so that the shell instead of being 70 substantially flat as heretofore, is substantially raised from the surface of the fabric or given a puffed appearance.

In carrying out my invention I preferably form the stitches of a single shell or 75 cluster from a plurality of centers in accordance with the method of operation herein disclosed. Said method is not herein claimed, but will be set forth herein for the purpose of securing completeness and clearness of disclosure. In practising said method to produce the said article I may and preferably do employ a crochet or overseaming machine of the general type disclosed in the patent to Merrow, No. 428,508, 80 May 20, 1890, although it is obvious that any suitable means may be employed for producing the border referred to, or that it may be produced in any suitable manner. Preferably, however, the border is a machine made one. The mechanism preferably employed includes an eye pointed sewing machine needle, a crochet hook or knitting needle, and a supplemental thread feeding hook. 85 90 95

Referring more particularly to the drawings, the frame of the machine, which I may employ in practising my method and in producing the novel border, is indicated at 1, the eye pointed sewing machine needle 100 herein represented as vertically reciprocable is indicated at 2, the crochet hook or knitting needle at 3 and the feeding hook for the supplemental thread at 4. These may

be positioned as indicated in the said Mervow patents and operated as therein disclosed or in any other suitable manner.

The presser foot is indicated at 5 and is 5 preferably spring pressed against the upper face of the fabric and is provided with the customary recess or opening for the passage of the needle 2. The fabric to which the ornamental border is to be applied is 10 introduced at the front of the machine or from the right viewing Fig. 1, and is passed in a step by step manner beneath the presser foot 5.

In order suitably to feed the fabric to 15 which the border is to be applied, I preferably provide a feed slide 6 having a serrated or saw tooth edge 7, the teeth whereof are inclined to the left as indicated in Fig. 1, and an extension 8 having a pin 9 received 20 in a slot 10 of a feed arm 11 pivoted at 12 upon the framing of the machine. Heretofore so far as I am aware, the fabric has been fed in a step by step manner in one direction only beneath the presser foot, each 25 cluster or shell being formed when the fabric is at rest. In accordance with my invention, however, I impart a step by step forward feeding movement to the fabric and also a comparatively slight rearward movement 30 following each forward movement. This adjunctive rearward movement is for the purpose of positioning the stitches of the shells or clusters in the manner already indicated. It is evident that any suitable 35 means may be employed to this end. Preferably, however, I employ a gear wheel 13 fast upon the shaft 14 and a pinion 15 fast upon a shaft 16 and having thereon an eccentric 17 receiving an eccentric strap 18 of an arm 40 19 having a slotted pivotal connection 20 with the feed arm 11. In this manner, the feed arm, and consequently the feed slide 6, are reciprocated in both directions. The extent of each forward feeding movement 45 is preferably materially in excess of the extent of the adjunctive or rearward feeding movement.

Upon a face of the gear 13 I suitably secure or form a cam 21 to under-ride and 50 elevate periodically the roll 22 loose upon a lever 23 pivoted at 23' upon the framing of the machine. The free end of the feed slide 6 rests upon the said roll 22 and the periodic elevation of said roll therefore periodically elevates the feed slide and simultaneously imparts a feeding movement thereto. Within the scope of my invention 55 one or more cams 21 may be employed.

In order to effect the rearward feed of the 60 fabric I provide the gear 13 with a cam 24 having a thin edge or portion 25, which in the rotation of the gear 13 is periodically brought beneath the roller 22 and thereby momentarily elevates the same to effect the 65 rearward feeding of the fabric. The gear 13

is represented as driven in the direction of the arrow adjacent thereto in Fig. 1 and the relation of the parts is such that when the cam 21 engages and lifts the roller 22, the eccentric 17 is moving the feed slide 6 to the left, viewing Fig. 1. Therefore, the feed slide when elevated into feeding relation to the fabric moves the same by means of the teeth 7 a suitable distance forward or to the left viewing Fig. 1. The continued rotation 70 of the gear 13 brings the cam 24 beneath the roller 22, thereby again to elevate the feed slide 6. When the feed slide 6 is momentarily elevated by the cam 24 the eccentric 17 has now reached such a position that it 8 imparts a rearward movement or movement to the right of the feed slide 6. Therefore the momentary engagement of the edge 25 of the cam 24 effects a slight rearward movement of the fabric. As shown in Figs. 1 and 85 2 the feed slide 6 is also provided with fabric engaging saw teeth 7' oppositely inclined with respect to the teeth 7, to effect the rearward feeding movement of the fabric. 90

The shell or cluster formed in accordance with the herein disclosed method may obviously have any suitable or desired number of stitches or loops and a preferred form thereof is represented at 8' in Fig. 3. By an 95 adjustment of the cams co-operating with the feed slide or by the employment of additional cams, I may, for example, form clusters of four, six or eight stitches or more. That form of mechanism herein represented 100 is adapted to produce ornamental borders, each shell whereof is composed of eight stitches. If desired, I may provide the edge of the fabric with a double row of shells. In such event, however, the outer overlying row 105 of shells is fashioned as herein described.

At the front of the machine and in the line of feed of the fabric I provide a preferably removable finger 26, shown in Fig. 6, the edge 27 of which acts as a former about or 110 with respect to which the loops or stitches are laid. This finger is preferably slid into the work face of the machine and may be readily removed. The inner end 28 of said finger extends somewhat to the left of the 115 needle 2, viewing Fig. 1, so that as the stitches are positioned by the needles, they are received by the narrowed inner end of said finger. The said finger is provided with a slight swell or shoulder 34 to hold the 120 initial stitches of the shell in the position in which they are laid and prevent them from being forced or crowded substantially to the left viewing Fig. 6.

In forming the ornamental border, I 125 may employ as indicated in Fig. 7, a main or sewing thread 30 fed by the sewing needle 2 and a thread fed by the hook or guide 4. I also provide a crochet hook or sewing machine needle 3, to which is imparted a 130

reciprocatory movement above and then beneath the face of the fabric and in substantial parallelism therewith. The needles 2, 3 may be operated in any suitable manner to 5 impart the desired movements thereto. Each stitch is made up of two lengths or portions of thread constituting a single bight or loop. The main thread 30 extends from the point 31 of the fabric constituting a 10 center from which certain of the stitches of the shell diverge. The hook of the knitting needle 3 is preliminarily positioned at the left of both threads and thereafter draws them to the right viewing Fig. 7 and positions them in the formation of the shell. 15 The needle 3 is then moved to the lower face of the fabric, thereby completing one cycle of movement and positioning a single stitch of the shell or cluster. This operation 20 is repeated until a suitable number of stitches to complete the shell are formed. The outer edge of the shell is formed of crocheted loops substantially as indicated in the Merrow Patent, No. 414,233, and the 25 supplemental thread, if employed, preferably enters into the crocheted portions of the loops.

If a double border, as indicated in Fig. 5, be desired, then after the fabric has been 30 run once through the machine and a single series of clusters 35 has been formed along or near its edge, the fabric is run again through the machine and the outer series of clusters 36 is formed in or upon the single 35 series or between it and the extreme edge, and extends outward therefrom as indicated in said figure.

Heretofore in the formation of borders composed of a series of shells or clusters 40 the stitches as laid or during the formation of each shell or cluster slide or are forced by succeeding stitches in the direction of the forward feed of the fabric. Therefore and assuming a cluster to be formed of eight 45 stitches, it is obvious that the first three or four stitches extend in a forward direction or generally in the direction in which the fabric is fed. The final stitches of the shell are extended in a direction opposite to the 50 forward feed of the fabric, because the sewing machine needle which introduces the main sewing thread and the knitting needle do not participate in the forward feeding movement of the fabric and hence tend to 55 draw the last formed stitches or loops of the shell rearwardly, or so that they radiate toward the right instead of toward the left and in the manner indicated in the Merrow Patents, No. 413,077 and No. 414,233. Intermediate 60 stitches or loops of the cluster extend directly outward, so that a general fan shaped effect is produced.

In carrying out my invention and assuming that the shell or cluster is composed of 65 eight stitches, a certain number of stitches,

say three, are laid from a single center, so that they diverge therefrom and then the remaining stitches of the said shell or cluster are laid from a closely adjoining center and diverge therefrom, but are grouped with the three first laid stitches, so as to form a single shell or cluster. In order that the completed shells or clusters may present a raised or puffed appearance and not lie substantially flat against the fabric, I provide an additional amount of thread to the 70 stitches as by forming said stitches about a relatively broad finger or former 26. Moreover I retain each stitch in the position 75 in which it is initially laid, at least until all the stitches of a cluster or shell are laid. In this manner the stitches are not distended and flattened but remain puffed or elevated. As the mechanism herein represented is adjusted the first three stitches of each shell 80 or those lettered A, B and C in Fig. 4, are laid when the fabric has been fed forward to a new position immediately following the formation of the preceding cluster or shell. Owing to the shape of the finger 26, these 85 three stitches practically do not slide forward, but are substantially held in their position as laid. These three stitches radiate 90 from the center a. Thereupon the fabric is moved to the rear slightly as described, so that the succeeding threads of the shell 95 radiate or extend from a new center b, which is very slightly in advance of the center a. Preferably the first threads of those laid from the center b, as, for example, threads 100 D, E, partially overlie the threads B and C, so that even though the threads B and C do radiate very slightly to the left, they are partially concealed by the overlying threads. In the same manner, the thread A may be 105 overlaid if desired, but this might in some cases unduly narrow the shell. Practically, however, the threads A, B and C do not in the disclosed embodiment of the invention 110 radiate toward the left, and the whole general effect of the threads or stitches of the shell is an inclination or curl toward the right, as clearly indicated in Fig. 3.

Inasmuch as in forming the shell or cluster as disclosed in the said Merrow patents, 115 all the stitches radiate from a common point, it is obvious that the tendency of each succeeding stitch was to crowd the others forwardly in the direction of feed of the fabric. By laying certain of the stitches from a new center as described, this tendency is overcome and all the threads extend in a direction opposite to the feed of the fabric. The outer edge of the shell is crocheted by the knitting needle or crochet hook 3, as substantially indicated in the Merrow Patent, 120 No. 414,233. The engagement of the knitting needle with the last stitch of each cluster or shell as the fabric is fed forward after the completion of the shell draws all the 125 130

threads toward the right,—that is, in a direction opposite to the feed of the fabric, as illustrated in Fig. 4.

From the foregoing description, it will be clearly understood that each of the several stitches making up any shell or cluster is primarily and predeterminedly laid in its proper position relative to all the other stitches of said cluster. For this reason, the said stitches preserve their original characteristics. They are originally laid with sufficient slackness or amount of thread to give them an elevated or fluffy appearance, and this appearance is not lost in, but is characteristic of the completed fabric. The stitches of a cluster are laid in their predetermined relative position, with a general trend in the same direction (in the present case, to the right) and then the fabric is fed forward and the engagement of the knitting needle with the last stitch of the cluster results in drawing all the stitches of that cluster still farther in the same direction (that is, to the right), but the relative position of the several stitches is preserved unimpaired, and is not broken up and disarranged as would be the case if the stitches were laid in lines radiating both to the right and to the left and then all the stitches were drawn to the right or to the left. Moreover, because the stitches are laid from two centers, the latter laid stitches of that cluster do not crowd out of place the earlier laid stitches of that cluster, as is necessarily the case where a relatively large number of stitches are all laid from a common center. Furthermore, because there is no drawing of the threads out of their relative positions, the threads are not subjected to undue tension, and hence the raised or fluffy appearance of the cluster is preserved, and it does not become flat.

Heretofore each set or cluster of stitches of a shell-like border, such as shown in the patent to Merrow, No. 414,236, has been intentionally composed of stitches radiating substantially from a single point, and the machine for making said fabric has been designed and constructed to secure the penetration of the fabric always at the same point for the formation of the entire set of stitches. In practice, however, this repeated

penetration of the fabric at the same point has tended constantly to displace the fabric very slightly, so that there is no distinct form given to the base of each set of stitches. In other words, all the stitches radiate from a single point or center of penetration, which, however, has no defined area and location. Therefore, it has been necessary to hold the work firmly, so as to prevent its displacement during the repeated needle penetration. In accordance with my invention, however, the first portion of the set of stitches penetrates the fabric at a distinct and common point, and then the fabric and the needle are relatively shifted, so that the succeeding portion of the stitches (and preferably the entire remaining portion of the stitches) penetrate the base or foundation fabric at an adjacent but distinct and common center, the stitches making up the second portion of the set of stitches overlying a part of the stitches of the first set and substantially confine or position them.

Having thus described one illustrative embodiment of my invention, I desire it to be understood that although specific terms are employed, they are used in a generic and descriptive sense and not for purposes of limitation, the scope of the invention being set forth in the following claim.

As a new article of manufacture, a stitch fabric border consisting of a base or foundation and a series of sets of stitches secured thereto, each set of stitches of said series being crocheted together in loops at their outer ends and arranged in a general shell or cluster formation, a portion of the stitches comprising each set diverging from a first or common center and a succeeding portion of the stitches comprising each set diverging from an adjacent but distinct and common center, and overlying and confining the basal parts of the stitches constituting said first portion.

In testimony whereof, I have signed my name to this specification, in the presence of two subscribing witnesses.

WILLIAM H. CARTER.
